CLAIM

The ornamental design for a reversible denim skirt, as shown and described.

DESCRIPTION

FIG. 1 is a front perspective view of a reversible denim skirt showing my new design;

FIG. 2 is a rear perspective view thereof;

FIG. 3 is a left side elevational view thereof; and,

FIG. 4 is a right side elevational view thereof.

The dashed lines shown in the figures represent a silhouette of an individual wearing a garment of the present designs, and forms no part of the current invention.

The claimed design in it's reversible condition is identical to what is shown and described.
